UNITED STATES PATENT OFFICE.

HENRY K. SANDELL, OF CHICAGO, ILLINOIS, ASSIGNOR TO HERBERT S. MILLS, OF CHICAGO, ILLINOIS.

PHONOGRAPH CONTROL DEVICE.

1,381,506.

Specification of Letters Patent. **Patented June 14, 1921.**

Application filed December 3, 1919. Serial No. 342,249.

To all whom it may concern:

Be it known that I, HENRY K. SANDELL, a citizen of the United States, residing at Chicago, in the county of Cook and State 5 of Illinois, have invented a new and useful Improvement in Phonograph Control Devices, (Case A,) of which the following is a specification.

The present invention relates to devices 10 for controlling the operation of phonographs, and more particularly to those whereby the rotation of the support for the sound record is started and stopped by the movement of the reproducer arm.

15 In accordance with the present invention, the rotation of the support for the sound record is controlled by the movement of the tone-arm or arm carrying the reproducer. Movement of this arm in one direction causes

20 the sound record support to rotate when the arm approaches a predetermined position, and the movement of the arm in the opposite direction causes the rotation of the sound record support to cease, likewise when the 25 arm approaches a predetermined position.

The movement of the arm within the predetermined positions does not in any way effect the rotation of the sound record support, which consequently, if in rotation, continues 30 to rotate until the tone or reproducer arm

has reached the stopping position, and if at rest, remains at rest until the tone or reproducer-arm has reached the starting position. In the accompanying drawings the 35 invention is illustrated in a specific embodiment, as applied to devices wherein the rotation of the sound record support is effected by means of an electrically driven motor. In the drawings,

40 Figure 1 is a plan view of a device embodying the present invention, a portion of the cabinet inclosing the same being broken away;

Fig. 2 is a side elevation thereof, partially 45 in section;

Fig. 3 is a detail view, in vertical section, of the tone-arm support;

Fig. 4 is a detail elevation of the interior 50 of the tone-arm support, viewed in the direction of the arrow 4 of Fig. 3, the support itself being sectioned;

Fig. 5 is a bottom plan view of the support containing the control mechanism;

Figs. 6 and 7 are separate details of construction;

Fig. 8 is a horizontal section on line 8—8 of Fig. 3;

Fig. 9 is a diagrammatic view of the electrical circuit showing the position of the control device therein.

Referring more particularly to the drawings, the numeral 10 indicates the cabinet upon which the phonograph is mounted, the numeral 11 indicating the top of this cabinet. Through a suitable opening in the 60 top 11 a rotatable shaft 12 protrudes, upon which is rigidly mounted the record support shown as a felt covered disk 13. Upon this any suitable sound record of the disk type 14 may be placed.

A tone-arm 15, carrying the reproducer needle 16 and capable of limited oscillation both vertically and horizontally is mounted upon a suitable support 17, preferably bell-shape, which is mounted upon the cabinet 70 top 11 by means of suitable bolts 18 or other attaching means. The support 17 is so positioned with respect to the table 13 that the tone-arm may swing over the record in proper position for reproduction of the 75 sounds recorded thereon.

The tone-arm 15 may be mounted upon the bell-support 17 in any suitable manner so that it may have a limited oscillation in both the vertical and horizontal direction. 85 In the construction illustrated, the end of the tone-arm 15 is formed as a conduit section 19, which is rotatably mounted upon the conduit section 20 formed with a cylindrical socket for the head 21 of the conduit section 90 22. The conduit section 22 extends vertically downward through an opening provided in the bell-support 17 and is provided with a shoulder 23 which rests upon the slightly flattened top of the support 17. 95

The socket 20 has a limited rotative movement with respect to the head 21 of the conduit section 22, and the conduit section 22 may rotate on a vertical axis with respect to the bell-support 17 carrying with it the 100 entire tone-arm.

The conduit section 22 fits into a verti-

cally disposed fitting or tube 24 which is fixed within the support by any suitable means, for example, by means of the horizontally projecting lugs 25, 25 which are attached, for example, by screws, to the projecting shoulders 27 formed integrally with bell-support 17. For attachment to the amplifier, the conduit section or tube 24 may be enlarged at its lower end 28, and formed with an internal enlarging taper, a shoulder 29 being provided at the point of enlargement. In order to limit the movement of the conduit section 22 within the tube 24, a pin 30 having a projecting head 31 is attached to the conduit section 22 within the bell-support 17, and an opening 32 of a limited arc is provided in the upper portion of the tube 24, through which the head 31 of pin 30 passes. A vertical slot 33 may be provided from the opening 32 to the top of the tube 24 to permit the fitting together of the parts.

In the present embodiment of the invention as specifically illustrated in the drawings, the control of the rotation of the table is effected by opening and closing a switch in the circuit of an electric motor driving the table. The switch proper is mounted upon a semi-circular ring section 34 of suitable insulating material, such as fiber. This ring section 34 is suitably fixed in position, resting upon the two fastening lugs 25 of the center tube 24 by means of the screws 26 which retain the latter in position. Upon this insulating section 34 is mounted an annular leaf or spring of conductive metal, such as copper, indicated by the numeral 35, and which extends for the greater portion of the circumference of a circle and forms one contact member of a switch. One end 36 of this conductive switch member is bent downwardly and passes through an opening in the insulating mount 34 for attachment of a conductive lead 37 from the motor circuit. At its other end the conductive member 35 extends beyond the end of the insulating member 34, describing in the specific form shown approximately a semi-circle before it terminates in a position just above a screw terminal and contact member 38 provided in the other end of the insulating member 34, and to which terminal the other lead 39 from the motor circuit is attached. This projecting portion of the conductive member 35 is spring like in nature and is provided intermediate the projecting portion with a quite sharp zigzag bend, whereby one portion is raised above the other portion, for a purpose more fully hereinafter described. In its normal position, when no downward pressure is exerted upon the conductive member 35, it will spring away from the terminal 38 and assume a position above the latter and out of contact with it.

In order to cause the conductive member 35 to make contact with the terminal 38 and to break contact at the determined position of the tone-arm, a suitable device involving a lost-motion is provided in such manner that the movement of the tone-arm will be effective in operating the switch only when the tone-arm is at the determined position. As embodied in the form of the invention illustrated, a slide 39 is mounted upon the conduit section 24 for movement relative thereto, for example, by means of the collar 40 embracing the tube section 24 just above the shoulder 29 and the collar 41 embracing the tube section 24 at a higher point. This slide is provided with an opening or slot designated by the numeral 42, through which the projecting head 31 of the pin 30 passes. This slot 42 is of less angular width than the slot 32 formed in the upper end of the tube 24. The sides of the slot 32 serve as limiting stops for the movement of the pin when the reproducer-arm is moved on its vertical axis, and this movement of the pin likewise causes a movement of the slide 39 when the head 31 of the pin 30 approaches one limit or the other of its movement. The total movement of the slide in any direction is slight, being substantially measured by the difference in angular width between the slot on the slide and that formed in the tube 24. In Fig. 4 of the drawings the pin is illustrated as at one limit of its movement, that reached when the tone-arm is moved to the point A indicated on Fig. 1. If the tone-arm is now moved in the direction of the point B, the pin 30 moves without causing any corresponding movement of the slide 39 until it approaches near the limit of its movement. The head 31 of the pin will then engage the opposite side of the slot 42 and carry the slide 39 with it until its limit of movement is reached. The return movement of the reproducer-arm from the position B to the original position A will produce a similar movement of the slide 39, which takes place only as the arm approaches its limit of movement in the opposite direction.

The slide 39 is provided with a projecting lug 43 of suitable insulating material, and preferably tapered at its lower edge, which lug contacts with the spring contact member 35 of the control switch. As previously described this contact member is provided with a zigzag bend 44 in such manner that a portion of this contact member is raised above the adjacent portion thereof, and this bend is so positioned that when the slide 39 is at one limit of its movement the lug 43 rests on the higher portion of the contact member, this corresponding to the position A of the tone-arm; and when the slide 39 is at the opposite limit of its movement, the lug 43 passes over the portion of the

member 35 at a lower level, this corresponding to the position of the tone-arm B. The resiliency of the member 35 tends to move it out of contact with the contact member 38, 5 as a result of which, when the lug 43 is positioned over the portion of the contact member 35 at the lower level, the latter rises and breaks contact with the member 38; and when the lug 43 moves over to the up- 10 per portion of the conduit member 35, the latter is forced down against the contact member 38 and the circuit is closed. By reason of the sharp incline between the two portions of the contact member 35, a relatively slight movement of the slide 39 in 15 either direction causes the opening or closing of the circuit. When opened it is not closed until the tone arm approaches the limit of its movement in one direction (A) 20 and when closed, it does not open until the tone-arm approaches its limit of movement (B) in the other direction. The circuit is indicated diagrammatically in Fig. 9, where numeral 50 indicates a feed wire connected 25 to the terminal 38; the other feed wire 51 is connected to one terminal of the drive motor 52, from the other terminal of which a conductor 53 extends to and connects with the end 36 of switch member 35.

30 Although the present invention has been described in connection with a specific embodiment thereof, it is not intended that the details of said embodiment are to be regarded as limitations upon the scope of the invention, except in so far as included in the accompanying claims:

I claim:

1. In combination with a record support, a pivotally mounted reproducer arm coöperating therewith and means for rotating said support, a conduit section connected with the reproducer arm in axial alinement with its pivotal center and movable with said arm, a movable slide, engaging means mounted upon said conduit section and capable of engaging said slide only as the tone-arm approaches the limit of its movement in either direction, and means for starting and stopping the rotation of the support by the movement of said slide.

2. In combination with a record support, a pivotally mounted reproducer arm coöperating therewith and means for rotating said support, a conduit section connected with the reproducer arm in axial alinement with its pivotal center and movable with said reproducer arm, a movable slide embracing said conduit section, engaging means mounted upon said conduit section and capable of engaging said slide only as the tone-arm approaches the limits of its movement in either direction, and means for starting and stopping the rotation of the support by the movement of said slide.

3. In combination with a record support, 65 a pivotally mounted reproducer arm coöperating therewith and means for rotating said support, a conduit section connected with the reproducer arm in axial alinement with its pivotal center and movable 70 with said arm, a slide embracing said conduit section and provided with an opening, an engaging pin secured to said conduit section and entering the opening in said slide, whereby the slide is moved for a limited distance as the tone-arm approaches the 75 limits of its movement in either direction, and means for starting and stopping the rotation of the support by the movement of said slide.

4. In combination with the movable reproducer arm of a phonograph, a control switch for the drive circuit of the phonograph, and means for operating the same, said means comprising a movable member 85 capable of engaging and releasing said switch to close and open the same, and means for operating said movable member only as the tone-arm approaches the limits of its movement.

5. In combination with the record support and the reproducer arm of a phonograph, a slide movable relatively thereto, an engaging member movable with the tone-arm and engaging the slide as the tone-arm approaches the limits of its movement to effect 95 movement thereof, a circuit control-switch in coöperative relation to said slide whereby it is opened and closed by the movement of the latter and electrical means controlled by 100 said switch for operating said record support.

6. In a phonograph control-device, a conduit section movable with the tone-arm of the phonograph, a slide movable relatively 105 thereto and provided with an opening, a pin carried by the conduit section and passing through the opening in the slide, whereby movement of the latter is effected when the conduit section approaches the limits of its 110 movement, a lug carried by the slide, and a control-switch comprising a fixed contact member and a movable contact member normally out of contact therewith and capable of being engaged by the lug on the slide at 115 one point in the movement of the latter to close the switch.

7. In a phonograph control-device, a conduit section movable with the tone-arm of the phonograph, a slide movable relative 120 thereto, engaging means carried by the movable conduit section and capable of engaging said slide when the conduit section approaches the limits of its movement in either direction, a control-switch comprising a fixed contact member, and a movable contact member, the latter being normally out of contact with the former, and means

whereby movement of the slide causes contact between the contact members to be established or broken.

8. In a phonograph control device, a tubular conduit section, a tone-arm supporting section movable within said conduit section and provided with a pin projecting through the opening in the former, a slid-

able member mounted on the conduit section and provided with an opening of less angular width than that of the conduit section, said pin likewise entering this opening, a rotatable record support, means for rotating the support, and means operated by the slide for starting and stopping said rotation. 10 15

HENRY K. SANDELL.
